[57] CLAIM

The ornamental design for a compact camera, as shown and described.

DESCRIPTION

FIG. 1 is a front elevational view of a compact camera showing our new design;

FIG. 2 is a rear elevational view thereof;

FIG. 3 is a top plan view thereof;

FIG. 4 is a bottom plan view thereof;

FIG. 5 is a right side perspective view thereof; and,

FIG. 6 is a left side perspective view thereof.

The broken line showing of printed indicia is for illustrative purposes only and forms no part of the claimed design.
